CLAIM

The ornamental design for a gaming system display with graphical user interface, as shown and described herein.

DESCRIPTION

FIG. 1 is a front elevational view of a first embodiment of a gaming system display with graphical user interface showing our new design;

FIG. 2 is a front elevational view of a second embodiment of a gaming system display with graphical user interface showing our new design;

FIG. 3 is a front elevational view of a third embodiment of a gaming system display with graphical user interface showing our new design;

FIG. 4 is a front elevational view of a fourth embodiment of a gaming system display with graphical user interface showing our new design;

FIG. 5 is a front elevational view of a fifth embodiment of a gaming system display with graphical user interface showing our new design; and,

FIG. 6 is a front elevational view of a sixth embodiment of a gaming system display with graphical user interface showing our new design.

The broken lines in FIGS. 1 to 6 of the gaming system display with graphical user interface are for the purpose of illustrating environment, and form no part of the claimed design.
